Harry Sebel, London, England

Application March 22, 1950, Serial No. 8,706

Term of patent 14 years

(Cl. D34—15)

To all whom it may concern:

Be it known that I, Harry Sebel, a subject of the King of Great Britain, residing at 13 Kinloss Gardens, Finchley, London N. 3, England, have invented a new, original, and ornamental Design for a Riding Toy, of which the following is a specification, reference being had to the accompanying drawings, forming part thereof.

Fig. 1 is a side elevational view of a riding toy embodying the new design and

Figure 2 shows a rear three-quarter perspective overhead view of the riding toy of Fig. 1.

I claim:

The ornamental design for a riding toy, as shown.

HARRY SEBEL.
